Des. 212,511
Patented Oct. 22, 1968

212,511

LIFEJACKET

Ralph G. Mallory, Orange, Conn., assignor to The B. F. Goodrich Company, New York, N.Y., a corporation of New York

Filed May 15, 1967, Ser. No. 7,123

Term of patent 14 years

(Cl. D71—1)

Fig. 1

Fig. 2

FIG. 1 is a front elevation view of a lifejacket embodying my new design; and

FIG. 2 is a side elevation view of the lifejacket shown in FIG. 1.

The rear surface of the lifejacket, not shown, is substantially the same as the front surface.

The elements shown in broken lines are included for illustrative purposes only.

I claim:

The ornamental design for a lifejacket, as shown and described.
